DESIGN FOR A CHRISTMAS TREE ORNAMENT

Millard Pretzfelder, St. Albans, N. Y., assignor to Paper Novelty Manufacturing Co., New York,
N. Y., a corporation of New York

Application February 3, 1936, Serial No. 60,960

Term of patent 14 years

To all whom it may concern:

Be it known that I, Millard Pretzfelder, a citizen of the United States, residing in St. Albans, county of Queens, and State of New York, have invented a new, original, and ornamental Design for Christmas Tree Ornament, of which the following is a specification, reference being had to the accompanying drawing, forming a part thereof.

Fig. 1 is a front view of a Christmas tree ornament, embodying my new design; and Fig. 2 is a side view thereof.

I claim:

The ornamental design for a Christmas tree ornament as shown.

MILLARD PRETZFELDER.
